UNITED STATES PATENT OFFICE

HENRY K. MULFORD, OF PHILADELPHIA, PENNSYLVANIA, ASSIGNOR TO NATIONAL DRUG CO., OF PHILADELPHIA, PENNSYLVANIA, A CORPORATION OF PENNSYLVANIA

DESIGN FOR AN ATOMIZER

Application filed November 20, 1929. Serial No. 33,506. Term of patent 14 years.

To all whom it may concern:

Be it known that I, HENRY K. MULFORD, a citizen of the United States, residing at Philadelphia, in the county of Philadelphia, and State of Pennsylvania, have invented a new, original, and ornamental Design for an Atomizer, of which the following is a specification, reference being had to the accompanying drawing, forming part thereof, in which—

Fig. 1, is a view in front elevation of an atomizer, showing my new design.

Fig. 2, is a side elevational view.

Fig. 3, is a bottom plan view of the same.

The salient features of my design reside in the ornamental effect produced by combining a conventional atomizer bulb with an elongated cylindrical liquid containing chamber, said chamber having at the top a disc-like closure extending outwardly of the liquid containing chamber.

I claim:

The ornamental design for an atomizer, as shown and described.

HENRY K. MULFORD.
